UNITED STATES PATENT OFFICE.

HENRY D. TAYLOR, OF ROCHESTER, NEW YORK, ASSIGNOR TO LIGHTNING LETTER OPENER COMPANY, OF ROCHESTER, NEW YORK, A CORPORATION.

MACHINE FOR OPENING ENVELOPS.

1,137,552.

Specification of Letters Patent. Patented Apr. 27, 1915.

Application filed April 20, 1914. Serial No. 833,266.

To all whom it may concern:

Be it known that I, HENRY D. TAYLOR, of Rochester, in the county of Monroe and State of New York, have invented a new and useful Improvement in Machines for Opening Envelops, which improvement is fully set forth in the following specification and shown in the accompanying drawings.

The present invention relates to machines for opening envelops, and more particularly to that type employing a cutting mechanism and a feeding mechanism for moving the envelops past the cutting mechanism in order that an edge of each of such envelops will be removed, an object of this invention being to provide a simple and inexpensive construction which will move the envelops along a guide to the cutting mechanism and will also cause the envelops to be alined against the guide in the event that they are not so presented to such guide in the first instance.

To this and other ends the invention consists in certain parts and combinations of parts all of which will be hereinafter described, the novel features being pointed out in the appended claims.

In the drawings: Figure 1 is a plan view of a machine embodying the present invention; Fig. 2 is a front view of the same machine; Fig. 3 is a side view; Fig. 4 is a vertical section on the line $a-a$, Fig. 2; Fig. 5 is a vertical section through the machine in a plane with the rear faces of the knives or cutters; Fig. 6 is a detail sectional view in a plane through the axes of the two inclined pulleys; and Fig. 7 is an enlarged detail view showing the grooved guide in proximity to the cutting mechanism.

In the embodiment of the invention here-illustrated, there is employed a base member preferably in the form of a pan 1 having a portion 2 projecting upwardly from one side thereof to act as a support for a table 3 which is adapted to support the envelops. This table is provided with an upwardly-extending flange 4 at its rear edge serving as a guide, said guide being formed with a longitudinally-extending V-shaped groove 5 which is formed with a recess 5^a in proximity to the opening 5^b through which the cutting mechanism operates.

The cutting mechanism is, in this instance, in the form of an upper cutter 6 and a lower cutter 7, both cutters having peripheral cut-

ting edges formed by beveling two disks, the cutting edges being such that they exercise little or no feeding action on the envelop. The peripheries of these cutters are revolved at the same speed, although the cutters have different diameters and rotate at different angular speeds. In this instance, a frame 8 is bolted at 9 to the bottom of the pan 1 so as to project upwardly from the latter at the rear side of the table 3. On this frame, the shafts 10 and 11, carrying respectively the cutters 6 and 7, are mounted, the cutters operating through the opening 5^b. The shaft 10 has a worm wheel 12 rigidly secured to one end thereof and is provided at its other end with a reduced portion 13 over which fits a collar 14 and a nut 15, the cutter 6 being held between the nut 15 and the collar 14. The shaft 11 is provided with a worm wheel 16 at one end and is reduced at its other end at 17. On this reduced portion 17, a collar 18 and a nut 19 are fitted, the cutter 7 being held between the collar 18 and the nut 19. The shafts are driven by a common worm 20 which meshes with the worm wheels 12 and 16, said worm being secured directly to the shaft 21 of the motor 22 which, by means of bolts 23, is secured to the frame 8.

For feeding the envelops, there may be employed a feeding mechanism comprising a feeding member preferably in the form of an endless belt 24 whose plane of operation is at an acute angle to the plane of travel of the envelops or to the table 3, the latter being provided with an opening 25 so that a portion of the belt travels in a straight line above the table while another portion of the belt travels in a straight line below the table. While the invention has been shown as employing a feeding member in the form of a belt whose plane of operation is at an acute angle to the plane of travel of the envelops, it is apparent that a feeding member of any other type performing substantially the same result is within the scope of the present invention. In this instance, the belt is substantially L-shaped in cross section and is made of rubber. It is supported on two inclined pulleys 26 and 27 which are grooved to receive the inner rib on the belt while the other portion of the belt projects to one side of the plane of the pulleys and has a curved face 28 which co-operates with the envelops to move them toward the guide and beyond

the cutting mechanism. The pulleys 26 and 27 have ball bearing connections 29 with the upper end of studs 20 which are supported, slightly inclined to the vertical, within a frame 31 that is bolted at 32 to an upstanding lug 33 on the pan 1. Driving connection between the pulley 27 and the shaft 11 may be established by providing a crown gear 34 on the pulley 27 to coöperate with the crown gear 35 on the nut 19.

For holding the envelops with pressure against the feeding member 24, a yieldingly supported pressure device is employed preferably in the form of a shoe 36 having its under face flat throughout the greater area thereof and extending from the guide flange over the effective straight portion of the feeding member and also over the receiving portion which moves toward the guide so that the envelops will be pushed or forced toward the guide, the forward or intake end of the shoe being deflected upwardly at 37 to permit the envelops to pass readily beneath it. In this instance, this shoe is supported by a noncircular stem 38 which projects upwardly from the upper face of the shoe and is guided within a sleeve 39, the upper end of the stem being reduced at 40 and surrounded by a spring 41 which normally presses the shoe 36 toward the feeding member, a nut 42 being arranged on the upper end of the stem 40 and serving to limit the downward movement of the shoe by coöperating with the upper end of the sleeve 39. The sleeve 39 may be supported by a cap-plate 43 which is bolted at 44 to the casing 45 which incloses the operating parts of the machine, the cap-plate 43 serving as a cover for the upper cutter. A chute 46 is provided in the side wall of the machine for receiving the chips from the cutting mechanism and discharging them to the exterior of the machine.

In the operation of the machine upon the starting of the motor, the cutters 6 and 7 are rotated and the feeding belt or member 24 turns. The envelops are presented to the forward end of the feeding belt and are engaged first by a receiving portion which projects above the table and travels toward the guide flange 4, thus shifting the forward end of the envelops toward such guide flange and beneath the intake or receiving end of the pressure foot or shoe to that portion of the belt which travels parallel to the guide flange so as to carry the envelops along such flange to and beyond the meeting point of the cutters. While the envelop is held between the feeding belt and the presser foot, the forward or receiving portion of the belt is acting on the envelop and crowding the latter against the guide flange. This crowding of the envelop causes the latter to assume the shape of the groove in the guide flange and to bulge upon the contents. Im-

mediately before the envelop reaches the cutters, the bulged portion spreads into the opening or recess 5^a of the guide away from the contents so that the edge of the envelop is presented to the cutters free of the contents. At the time that the bulged portion of the envelop spreads into this opening 5^a, the envelop is held by the straight portion of the belt so that such envelop cannot tilt or tip into the notch. The presser foot does not extend to the rear curve of the feeding belt so that the belt discharges the envelops in a straight line by the straight portion.

A machine for opening envelops constructed in accordance with this invention embodies but few parts and is not liable to get out of order. The feeding member is such that it feeds the envelop against the guide which directs the envelops to the cutting mechanism and also carries the envelops in a straight line after such deflection. The feeding mechanism as a whole crowds or forces the envelops against a grooved guide so that the envelops are caused to assume the shape of the guide, after which the bulged portions spread into a notch away from the contents of the envelops, and the envelops as a whole are prevented from tipping or tilting during such spreading.

What I claim as my invention and desire to secure by Letter Patent is:

1. In a machine for opening envelops, the combination with a cutting mechanism, and a guide for directing envelops to the cutting mechanism, of a feed member having an endless face for coöperating with the envelops, said face moving in a plane at an acute angle to the path of travel of the envelops, the receiving portion of said feed member being movable toward the guide in order to carry the envelops to the guide.

2. In a machine for opening envelops, the combination with a cutting mechanism and a guide for directing envelops to the cutting mechanism, of a feeding belt moving in a plane at an acute angle to the plane of travel of the envelops in order that said belt may feed the envelops toward the guide and then carry them along the guide.

3. In a machine for opening envelops, the combination with a cutting mechanism and a guide for directing envelops to the cutting mechanism, of a table for supporting the envelops, and a feed member operable through the table and having an endless face for coöperating with the envelop, said face moving in a plane at an acute angle to the table and having the receiving portion movable toward the guide in order to carry the envelop to the guide.

4. In a machine for opening envelops, the combination with a cutting mechanism, a guide for directing envelops to the cutting mechanism and a table for supporting the envelops, of an endless belt operating

through the table and having its engaging face moving in a plane at an acute angle to the table, the belt being directed toward the guide at the receiving portion and then being directed substantially parallel with the guide for carrying the envelopes along the guide.

5. In a machine for opening envelopes, the combination with the cutting mechanism 10 and a guide for directing envelopes to the cutting mechanism, of an endless belt having a work engaging face moving in a plane at an acute angle to the plane of the envelopes passing through the machine, the 15 receiving portion of said belt being directed toward the guide and another portion of said belt being directed substantially parallel with the guide.

6. In a machine for opening envelopes, the 20 combination with the cutting mechanism and a guide for directing envelopes to the cutting mechanism, of an endless belt having a work engaging face moving in a plane at an acute angle to the plane of the envelopes passing through the machine, the receiving portion of said belt being directed toward the guide and another portion of said belt being directed substantially parallel with the guide, and a device coöperating 25 with the last mentioned portion of the belt to hold the envelopes against the belt.

7. In a machine for opening envelopes, the combination with a cutting mechanism and a guide for directing envelopes to the cutting 30 mechanism, of an endless belt having a work engaging face moving in a plane at an acute angle to the envelopes passing through the machine, the receiving portion of the belt being directed toward the guide and another portion of the belt being directed 35 substantially parallel with the guide, and a yieldingly-mounted pressure foot coöperating with the parallel portion.

8. In a machine for opening envelopes, the 40 combination with a cutting mechanism and a guide for directing envelopes to the cutting mechanism, of an endless belt having a work engaging face moving in a plane at an acute angle to the envelopes passing through the machine, the receiving portion of the belt being directed toward the guide and another portion of the belt being directed substantially parallel with the guide and a yieldingly mounted pressure foot coöperating 45 with the parallel portion and also with a portion of the receiving portion, the receiving end of said foot being deflected away from the belt.

9. In a machine for opening envelopes, the 50 combination with the cutting mechanism, a guide for directing envelopes to the cutting mechanism and a table for supporting the envelopes, said table being provided with an opening, two pulleys arranged in said opening and having their plane of movement at

an acute angle to the plane of the table and an endless belt passing about said pulleys so that the receiving portion of the belt is directed toward the guide and another portion of the belt travels parallel with the 70 guide slightly above the table.

10. In a machine for opening envelopes, the combination with the cutting mechanism, a guide for directing envelopes to the cutting mechanism and a table for supporting the envelopes, said table being provided with an opening, two pulleys arranged in said opening and having their plane of movement at an acute angle to the plane of the table and an endless belt passing about 75 said pulleys so that the receiving portion of the belt is directed toward the guide and another portion of the belt travels parallel with the guide slightly above the table, and a spring-pressed pressure foot supported above the table for coöperation with the straight portion of the belt and with a portion of the receiving portion of the belt.

11. In a machine for opening envelopes, the combination with a cutting mechanism 90 and a guide for directing the envelopes toward the cutting mechanism, an opening being provided in advance of the cutting point of the cutting mechanism, of feeding mechanism for feeding the envelopes to the cutting mechanism, said feeding mechanism having provision for forcing the envelopes with pressure against the guide to cause the envelopes to bulge on their contents so as to spread into the opening in advance of the 95 cutting mechanism free from their contents, said feeding mechanism also acting at a point beyond the cutting point in order to prevent the tilting of the envelopes into the opening in advance of the cutting point. 100

12. In a machine for opening envelopes, the combination with a cutting mechanism and a guide for directing envelopes to the cutting mechanism, an opening being provided in advance of the cutting point of the cutting mechanism, of a feeding mechanism embodying devices for coöperating with opposite sides of the envelopes to force the latter against the guide in order to cause the envelopes to bulge on their contents so 110 that the bulge portion may spread into the opening in advance of the cutting mechanism free from the contents, one of said feed members being in the form of an endless belt which extends from a point in advance of the cutting point to a point beyond the cutting point and other of said feed members coöperating with said belt from a point in advance of the cutting point to a point beyond the cutting point so 115 that the envelope is prevented from tilting into the opening in advance of the cutting point.

13. In a machine for opening envelopes, the combination with a base portion having 120

an integral table supporting portion projecting upwardly from one side thereof, a flanged table supported on said table supporting portion, a cutting mechanism supported on the base portion in rear of the table to coöperate with envelope movable on the table, and a casing cover for said cut-

ting mechanism coöperating with a base portion and with the table flange to inclose the cutting mechanism.
